MEASURING THE DUSTINESS OF PARTICULATE SOLIDS

Elmer A. Fike, Nitro, W. Va., assignor to Monsanto Chemical Company, St. Louis, Mo., a corporation of Delaware

Application October 29, 1953, Serial No. 389,017

2 Claims. (Cl. 88—14)

The present invention relates to a method for measuring the dustiness of particulate solids and to a device useful for this purpose.

The dustiness of particulate solids is invariably objectionable. The dust is often irritating and the extraneous matter introduced into the atmosphere settles as dirt, removal of which is both an expense and a nuisance. The result has been continual striving toward methods of reducing dustiness, as for example by treating with waxes, heavy metal soaps or the introduction of humectants and careful control of the moisture content. In the detergent field the problem is particularly acute since the dust of synthetic detergents is irritating to the mucous membranes causing sneezing and discomfort. The dry alkyl benzene sodium sulfonates for example are normally dusting synthetic detergents. Various agents have been discovered which mitigate the dustiness but as is generally the case the solution of the problem goes hand in hand with the development of suitable analytical methods. Heretofore a suitable method of evaluating dustiness of particulate solids has not been available.

In accordance with the present invention it has been discovered that a dust evaluation based upon the measurement of light transmitted through a dust cloud raised by the falling particulate solids gives reproducible and significant results. The details of the method will be clear on reference to the accompanying drawings.

Referring to the drawings, Fig. 1 is a perspective view of the dust measuring device. Fig. 2 is a cross sectional view from the front of the instrument. Fig. 3 is a cross sectional view from the end of the instrument. Fig. 4 is a detailed plan of the funnel arrangement for introducing the test material. Fig. 5 is a detail of a section of the feed tube illustrating the dismantling.

Referring to Fig. 1, the instrument comprises an opaque container or housing which may be constructed of stainless steel, aluminum or wood resting on a wooden base 2. The door 3 serves for removing the sample after the test has been run. On one side in the upper portion of the housing is a support 4 enclosing a photoelectric cell 5. The current from the cell is measured by a microammeter 6. The current, in turn, depends upon the intensity of light reaching the photoelectric cell from a constant source of light on the opposite side of the test chamber. In other words, the current is a function of the degree to which the dust in the atmosphere of the chamber obstructs the passage of light. The source of light and hence the current is adjusted to a constant value before each test by means of the rheostat 7. The material to be tested is placed in the funnel 9 which is made of either metal or glass from which it falls through the tube 8 into the test chamber. The feed tube 8 is preferably constructed of aluminum but other metals or glass serve equally well.

Referring to Fig. 2, a sample of the material to be tested is introduced into funnel 9. A 100 gram sample is convenient where the dimensions of the test chamber are width 12 inches, height and depth 7½ inches. The

2

plug 14 is connected to the power source through a voltage regulator not shown. The circuit to the light source 11 is then closed by means of switch 10, the light being focused by lens 12 on the photoelectric cell 5.

5 The current of the latter recorded by the microammeter 6 is adjusted to a constant value, say 100 microamperes, by means of the rheostat. Thereupon the test material in the funnel is introduced into the chamber.

Referring to Fig. 4, the material is released by striking the plunger knob 9c which depresses the stopper 9d. The latter is held in place by the spring 9e working against the brace 9b through which passes the plunger shaft 9f. Note that the brace is in the upper portion of the funnel so as not to interfere with the flow of the test sample. A ¾ in. funnel opening and a 2 in. I. D. feed tube have been found satisfactory so that upon striking the plunger knob the test material falls rapidly into the tray 15 of the test chamber—see Fig. 2. This raises a cloud of dust in the space above the collected solid. A stop watch is started when the plunger is depressed and readings taken every 5 seconds on the microammeter. In this connection it is preferable that the falling material does not intercept the beam of light to the photoelectric cell but that the opening for the feed tube is located in front of it as illustrated or behind so that the obstruction of light is solely from the dust. In practice it has been found convenient and desirable to take the lowest reading noted on the microammeter as the 5 second reading. Readings are then taken every 5 seconds for 100 seconds or until substantial equilibrium is reached.

Typical data are set forth below employing as the test material a detergent composition consisting essentially of 40% dodecyl benzene sodium sulfonate and 60% sodium sulfate. The data show duplicate runs on the same test material, illustrating the reproducibility of the data and also comparing the dustiness of an untreated control with the same material treated with approximately 1% on the detergent of a dust abating additive, as for example one of the dust abating products described in my co-pending application Serial No. 289,910, filed May 24, 1952, now Patent No. 2,744,874.

45	Seconds	Untreated			Treated		
		Run 1	Run 2	Ave.	Run 1	Run 2	Ave.

	95			88			96
	100	87	90	88	97	97	97
	Dust value			2,030			520

65 The dust values are reported in microampere seconds obtained as follows: The precision of measurement is adequate by making the approximation that for each 5 second interval the current of the photoelectric cell is constant. In other words, each 5 second reading is multiplied by five to give the approximate current of that 5 second interval. The summation of all these values then provides the total current in microampere seconds. Of course it is more convenient simply to add up all

the readings and multiply the total by five. Obviously it is possible to plot the data, plotting current against time in seconds, and obtain the precise value of the area under the curve by means of a planometer. However, this proved to be entirely unnecessary. The results are reproducible within about 10% making the approximation described. Furthermore, it is not known how much of this variation should be assigned to the method of measurement and how much to the non-homogeneity of the samples. Of course the more dusty the test material is the lower the current recorded whereas it is preferable to express increased dustiness by higher, not lower figures. Therefore, the dustiness is expressed as the difference in microampere seconds of what it would be in the absence of dust. If the current is adjusted to 100 microampères per second before the test, it is apparent that after 100 seconds the total would be 10,000 microampere seconds in the absence of dust. Accordingly, the dust value in microampere seconds is obtained by the following formula: Dust value = $10,000 - 5T$ where T is the total of the readings taken at the 5 second intervals.

It will be apparent that an accumulative wattmeter could be used instead of an ammeter and if sufficiently sensitive would be preferable as this would avoid the approximation discussed above and give the total power output directly. However, accumulative wattmeters of the required sensitivity are not generally available.

The removal of the sample in preparation for carrying out other tests is easily accomplished. Referring to Fig. 3, the door 3 is opened and the tray 15 removed and emptied. A jointed feed tube as illustrated in Fig. 5 has been found convenient as this permits dismantling and storing of the parts in the body of the chamber for shipment or storage. Two 10 inch sections or an overall length of 20 inches for the feed tube is recommended.

It is intended to cover all changes and modifications

of the examples of the invention herein chosen for purposes of disclosure which do not constitute departures from the spirit and scope of the invention.

What is claimed is:

- 5 1. A method of evaluating the dustiness of a particulate solid which comprises dropping a given quantity of said particulate solid from a given height, after the solid has fallen, measuring the extent to which dust in the atmosphere above the solid reduces the light transmission across a section of the space above the solid by determining the light transmission at frequent intervals until substantial equilibrium is achieved and summing the results.
- 10 15 2. A method of evaluating the dustiness of a particulate solid which comprises dropping a given quantity of said particulate solid from a given height into a confined space, after the solid has fallen, measuring the extent to which dust in the confined space of the container above the solid reduces the transmission of light across a cross section of said confined space above the solid by recording the minimum light transmission after falling, recording the light transmission at frequent intervals thereafter until substantial equilibrium is reached and summing the results.
